(74) *Attorney, Agent, or Firm* — Daniel M. Cohn; Howard M. Cohn

(57) **CLAIM**

The ornamental design for a container for food as shown and described.

DESCRIPTION

FIG. 1 is a perspective view of a container for food showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an exploded perspective view of the container for food; and,

FIG. 10 is a perspective view of the container for food shown in an open configuration.

The dash-dash broken lines in the drawings depict portions of the container for food that form no part of the claimed design.

1 Claim, 10 Drawing Sheets
